UNITED STATES PATENT OFFICE.

WALTER B. BROWN, OF NEWARK, NEW JERSEY, ASSIGNOR TO THE BIGELOW CARPET COMPANY, OF NEW YORK, N. Y.

DESIGN FOR CARPET.

SPECIFICATION forming part of Design No. 23,484, dated July 17, 1894.

Application filed June 22, 1894. Serial No. 516,428. Term of patent 3½ years.

To all whom it may concern:

Be it known that I, WALTER B. BROWN, a subject of the Queen of Great Britain, residing at Newark, in the county of Essex and State of New Jersey, United States of America, have invented and produced a new and original Design for a Carpet, of which the following is a full, clear, and exact description, reference being had to the accompanying drawing, forming a part thereof, which represents a face view of a carpet in which the new design is embodied.

The invention relates to a design to be worked into or upon surfaces, such as carpets or similar fabrics, and it consists in the novel configuration of the figures as herein shown and claimed.

The design consists of a body A and a border B. The body A is decorated with connected leaf scrolls, reversely curled, rosettes appearing within the scrolls, and leaf figures in festoon arrangement between the scrolls. The border B is decorated with a chain of leaf scrolls reversely curled, a rosette being contained in each scroll.

I claim—

1. In a design for a carpet, the body A, substantially as shown.
2. In a design for a carpet, the border B, substantially as shown.
3. The design for carpets, consisting of the body A and the border B, substantially as shown.

WALTER B. BROWN.
